RAILWAY CAR CONSTRUCTION

Frank Ditchfield, Cleveland, Ohio, assignor to
The Youngstown Steel Door Company, Cleve-
land, Ohio, a corporation of Ohio

Application August 24, 1935, Serial No. 37,716

23 Claims. (Cl. 105—409)

This invention relates to improvements in railway car construction.

For the purpose of rendering productive certain wood sheathed house cars, a large number of which are owned by the railroads, a repair construction has been conceived, developed and at the present is being successfully employed by virtue of which this purpose has been attained with a minimum of expense. Briefly, this repair construction involves salvaging of the metallic underframe of the cars and their reemployment with metallic car sides substituted for the deteriorated wooden sides of the repaired cars. It is customary in these repairs to dispose the posts and metallic sheathing of the new car sides outwardly of the side sills of the underframe to thereby obtain a metallic car of increased cubical capacity.

There are, however, certain types of railway cars to which such repair construction is not applicable. Notable of these types is the gondola car in which the spacing of the side sills of the metallic underframe is of such extent that the hereinabove briefly referred to repair construction cannot be utilized. The limitation as to width of car imposed by the tunnel clearance diagram which controls car design precludes the use of such repair construction. This condition applies as well to some constructions of house cars and the repair construction of the instant invention is directed to these cars as well as to cars wherein increased width is not a desideratum.

Applicant is thus confronted with and it is the main object of this invention to overcome the problem of releasing the capital investment represented by these cars and in an economical and facile manner to convert them to the category of revenue producing rolling stock of the railroads.

It is a further object to attain these ends by the utilization of the metallic underframes of these cars which are still serviceable and so reclaim an essential part thereof.

With these and other objects in view which will become clear as the description of the invention proceeds, this invention comprises the novel structure and combination of parts hereinafter described and particularly pointed out and defined in the appended claims.

In the drawings forming part of this specification—

Figure 1 is a fragmentary elevation of a portion of the side wall of a railway house car em-

bodying the instant invention, the roof being omitted for the sake of clearness.

Figure 2 is a vertical section taken on line 2—2 of Figure 1.

Figure 3 is a vertical section taken on line 3—3 of Figure 1.

Figure 4 is a vertical section taken on line 4—4 of Figure 1.

Figure 5 is a vertical section taken on line 5—5 of Figure 1.

Figure 6 is a horizontal section taken on line 6—6 of Figure 1.

Figure 7 is a horizontal section taken on line 7—7 of Figure 1, and

Figure 8 is a horizontal section taken on line 8—8 of Figure 1.

Figure 9 is a detailed elevation of a securing member.

In Figure 1 of the drawings there is illustrated the portion of a car side wall construction applicable to a repaired or converted car, and to new car construction, extending from and including a portion of the door opening provided in said side wall to one end thereof. It will be understood that the remaining portion of the car side wall is complementary to that shown and that the car side wall construction on the opposite side of the car is of similar construction.

The railway house car illustrated is designated generally by the reference numeral 10 and the particular car chosen to illustrate the invention is a converted house car built upon an underframe of an original gondola car. The underframe comprises essentially a center sill, not shown, and cross members 11, two of which are shown in Figure 1 of the drawings. To the ends of the cross members there is secured side sills 12. Each of these side sills is of channel shape in section and embodies a vertically disposed web 13 and inwardly extending upper and lower horizontal flanges 14 and 15. Each of the side sills 12 is preferably reinforced by means of a member 16 where such side sill extends across the door opening 17. The spacing of the side sills of a gondola car is usually large, the spacing of the sills of the underframe illustrated being 9' 5 1/8".

Upon the hereinabove described underframe the side walls of the converted car are erected preferably in the form of preassembled units. Each of the side walls embodies a Z-shaped side plate 18 extending from end to end of the car and arranged with its web 19 in a substantially horizontal plane, its inner flange 20 extending vertically upwardly and its outer flange 21 extending vertically downwardly from the web. 55

The side plate 18 is reinforced across the door opening 17 and for a desired distance beyond said door opening by means of a metallic member 22 preferably in the form of a channel. The reinforcing member 22 is arranged with its web 23 vertical and secured to the upstanding flange 28 of the side plate 18 as by means of rivets 24. The upper and lower flanges 25 and 26 of the reinforcing member 22 extend inwardly of the car.

Door posts 27 which define the horizontal extent of the door opening and intermediate posts 28 of the car side wall construction extend between the side plate 18 and the side sill 13 of the car underframe. Each of the door posts 27 is Z-shaped in section and is arranged with its web 29 substantially parallel to the side wall, its flange 30 extending inwardly at right angles to said side wall and its flange 31 extending outwardly at right angles to the side wall. At its upper end each door post is secured to the depending leg 21 of the side plate 18 as by means of rivets 32 extending through the web 29 of the door post and through said depending leg of the side plate. Additionally, each door post is secured to the reinforcing member 22 which, as clearly shown in Figure 4 of the drawings, extends downwardly below the web 19 of the side plate and provides, together with said web and the leg 21 of the side plate, a pocket or space for the reception of the upper end of each of the door posts. The securing to the reinforcing member 22 is effected by means of an angle member 33, one leg 34 of which is secured as by means of rivets 35 to the inwardly directed leg 30 of the door post while the other leg 36 is secured to the web 23 of the reinforcing member 22 as by means of rivets 37.

Certain of the intermediate posts as well are disposed with their upper ends extending into the pocket or space defined by the side plate and its reinforcing member. Each intermediate post is of Z shape in section and arranged relative to the car side wall so that its web 38 is at right angles thereto and the inner and outer flanges 39 and 40 are parallel thereto. The upper end of each intermediate post 28 is secured to the side plate 18 as by means of rivets 41 extending through the leg 40 of the post and the leg 21 of the side plate. The first mentioned intermediate posts 28 are, additionally, secured to the side plate reinforcing member 22 by means of an angle member 42, one leg of which is secured to the web 38 of the intermediate post by means of rivets 43, while the other leg 44 is secured to the web 23 of the reinforcing member as by means of rivets 45.

Metallic sheathing comprised of a plurality of metallic sheets 46 is secured along its upper margin to the depending leg 21 of the side plate 18 as by means of rivets 47. The metallic sheets 46 are, additionally, secured upon the outside of the door posts as by means of rivets 48. The metallic sheets are lapped upon the intermediate side posts 28 and secured to the leg 40 thereof as by means of rivets 49. Adjacent the ends of the car the last metallic sheet 46 is secured to the intermediate post as by means of rivets 50.

The metallic sheets 46 terminate, as clearly illustrated in Figure 3 of the drawings, above the side sills 12. These sheets are fastened to the side sill by means of an angle member 51 the lower margin of said sheets being riveted to the outside of the upstanding vertical leg 52 of said angle member by means of rivets 53. The hori-

zontal leg 54 of the connecting angle member 51 is disposed upon the upper flange 14 of the side sill and secured thereto as by means of rivets 55. The horizontal leg 54 is preferably extended inwardly beyond the horizontal flange 14 of the side sill to provide a supporting means for the floor 56 of the car to which it is secured as by means of bolts 57.

Means is provided for the securement of the lower ends of the door and intermediate side posts to the side sill whereby a rigid, sturdy connection is obtained, thus enabling the side wall construction to function as a girder for the purpose of carrying a portion of the stresses incident upon the car underframe. Referring, first, to the securement of the intermediate side posts to the side sill, this securement together with the means utilized therefor is clearly illustrated in Figures 3 and 7 of the drawings. There is utilized a securing member 58 preferably in the form of a casting although it is to be understood that the securing members may be formed of structural elements or pressings if desired. Each securing member 58 for the intermediate side posts embodies a vertical upstanding leg 59 and a horizontal inwardly extending leg 60. A pair of spaced post attaching flanges 61-61 extend at right angles from the legs 59 and 60 and are arranged so as to straddle the web 38 of an intermediate side post. The securing members are disposed upon the inside of the connecting member 51, the vertical leg 59 of each securing member 58 being riveted to the upstanding vertical leg 52 of the connecting member 51 and to the lower margin of the metallic sheathing as by means of rivets 62. The inwardly extending leg 60 of the securing member 58 is secured to the upper flange 14 of the side sill as by means of rivets 63 which pass through the horizontal leg 54 of the connecting member 51 and said upper flange of the side sill. The post attaching flanges 61 are riveted to the web of the intermediate side post as indicated at 64.

The securing member 58 for each intermediate side post is thus secured by means of a horizontal series of rivets to the upper flange of the side sill. Additionally, each securing member 58 is rigidly secured to the web 13 of the side sill 12. To this end the securing member 58 is provided with a depending attaching flange 65 extending downwardly from the horizontal leg 60 in abutting engagement with the outside of the web 13. The attaching flange 65 is secured to said web as by means of rivets 66. In order to permit riveting of the attaching flange 65 to the web of the side sill, the horizontal leg 54 of the attaching member 51 is coped, as indicated at 67, whereby the attaching flange 65 extends through said member 51 for securement to the web of the side sill. By virtue of this construction it is apparent that each intermediate side post is rigidly secured to the side sill by securing means in two planes at right angles to each other, thereby providing a sturdy connection.

A similar securement between the lower ends of the door posts and the side sills 12 is employed. The connecting member 68 utilized for the attachment of each door post to the side sill is clearly illustrated in Figures 1, 5 and 6 of the drawings. This connecting member comprises a vertical upstanding leg 69 and a horizontal inwardly extending leg 70. One portion 71 of the vertical leg 69 is disposed against the inner face of the upstanding leg 52 of the attaching member 51 which terminates adjacent the inwardly

extending leg 30 of the door post, as clearly shown in Figure 6 of the drawings. This portion 71 is secured as by means of rivets 72 to the upstanding leg 52 and the lower margin of the metallic sheathing. The other portion 73 of the upstanding leg 69 is disposed against the inner face of the web 29 of the door post and is riveted to said web and the lower margin of the metallic sheathing as indicated at 74. The inwardly extending leg 70 is disposed upon the inwardly extending leg 54 of the member 51 and upon a floor supporting plate 75 disposed in the door opening and is riveted, as indicated at 76, to the upper flange 14 of the side sill 12. Post attaching flanges 77 extend at right angles from the upwardly and inwardly extending legs 69 and 70 and are riveted to the inwardly extending leg 30 of the door post as indicated at 78.

Each connecting member 68 is also secured to the web 13 of the side sill. For this purpose the connecting member 68 is provided with a depending attaching flange 79 which underlies and is secured to the downwardly extended portion of the web 29 of the door post as by means of rivets 80. This securing of the attaching flange 79 to the downwardly extending portion of the web 29 of the door post occurs in spaced relationship to the web of the side sill and, in order to provide for the securing of the attaching flange 79 of the connecting member 68 to the side sill, said flange is provided with inwardly offset ends 81 and 82 which abut the web 13 of the side sill and are riveted thereto as indicated at 83. Thus, in the case of the door posts, securing of the lower ends thereof to the side sill in planes at right angles to each other is obtained.

As indicated hereinabove, the side wall construction described is preferably preassembled into a unit and subsequently attached to the existing side sills. There are certain types of gondola cars, however, which do not utilize members separate from the side sheathing as side sills. In the conversion of this type of gondola car and in the conversion of cars wherein the side sills must be replaced, the side sill utilized may be embodied as a part of the car side wall unit. The incorporation of the side sill into the side wall unit, moreover, eliminates the problem of securely blocking the side wall unit which is present when the side sill is eliminated therefrom inasmuch as the side wall unit may then be supported upon the side sill. Wooden lining for the car side wall is indicated at 84. This lining is disposed against the inner faces of the door and intermediate side posts and secured in position by means of vertical nailing strips 85 secured to the car sheathing by means of clips 86.

The car ends, one of which is partially shown in Figure 8 of the drawings, and designated by the numeral 87, are provided with side flanges 88 arranged in overlapping relationship with respect to the vertical margin of the metallic sheathing. The flanges 88 are secured by means of the rivets 50 which fasten the vertical margin of the sheathing to the adjacent post 28.

A roof construction for the car 10 is indicated generally by the reference numeral 89.

It will be observed from Figures 3, 5, 6 and 7 of the drawings that the intermediate side posts and the inwardly extending leg of the door post terminate above the side sill. It will be apparent, as well, that the intermediate side posts and said leg of the door post lie vertically above the side sill for the main portion of the depth

of said posts and leg so that encroachment upon the tunnel clearance line is avoided.

It will be apparent that numerous changes and modifications of the details of the instant invention may be resorted to by those skilled in the art. It is, therefore, intended to comprehend all such changes and modifications within the purview of the invention, which is to be limited only by the appended claims.

I claim:

1. A railway house car converted from a gondola car comprising original underframe members of said gondola car including cross bearers and side sills secured to the end portions of said cross bearers, metallic door posts, metallic intermediate posts disposed above said side sills, means securing the lower ends of said posts to said side sills, side plates, means securing the upper ends of said posts to said side plates, metallic sheathing secured to said side plates and to the outside of said posts, said sheathing stopping short of said side sills and means secured to the lower margin of said sheathing and extending inwardly therefrom and fastened to said side sills, said first mentioned means having flanges arranged on the inside of said means fastening the sheathing to said side sills in parallel relation to said sheathing, said means being secured to the lower margin of said sheathing.

2. A railway house car comprising a metallic underframe including a side sill, a metallic side plate, metallic sheathing, means securing said sheathing to said side plate, means securing said sheathing to said side sill, metallic posts terminating above said side sill and secured at their upper ends to said side plate, said sheathing being secured to the outside of said posts, and brackets for securing the lower ends of said posts to said side sill, the body portions of said brackets being disposed between said means securing said sheathing to said side sill and said posts, said body portions comprising flanges secured to the lower ends of said posts, flanges extending downwardly from said body portions through said latter sheathing securing means, said downwardly extending flanges being secured to said side sill.

3. A railway house car comprising a metallic underframe including a side sill having a vertical portion and an upper substantially horizontal inwardly extending flange, a metallic side plate, metallic sheathing, means securing said sheathing to said side plate, means securing said sheathing to said side sill, metallic posts terminating above said side sill and secured at their upper ends to said side plate, said sheathing being secured to the outside of said posts, and brackets for securing the lower ends of said posts to said side sill, said brackets being disposed upon the inside of said means securing said sheathing to said side sill and each bracket comprising a substantially horizontal flange overlapping and secured to said inwardly extending sill flange, a vertical flange extending upwardly from said horizontal flange and secured to the lower end of one of said posts and a flange extending downwardly from said bracket through said sheathing securing means and secured to said vertical portion of the side sill.

4. A railway house car comprising a metallic underframe including a side sill having a vertical portion and an upper substantially horizontal inwardly extending flange, a metallic side plate, metallic sheathing, means securing said sheathing to said side plate, means securing said

sheathing to said side sill, metallic posts terminating above said side sill and secured at their upper ends to said side plate, said sheathing being secured to the outside of said posts, and 5 brackets for securing the lower ends of said posts to said side sill, said brackets being disposed upon the inside of said means securing said sheathing to said side sill and each bracket comprising a substantially horizontal flange overlapping and 10 secured to said inwardly extending sill flange, a vertical flange secured to said means securing said sheathing to said side sill, a vertical flange extending at substantially a right angle to said first-mentioned bracket flanges and secured to 15 the lower end of one of said posts and a flange extending downwardly from said bracket through said sheathing securing means and secured to said vertical portion of said sill.

5. A railway house car comprising a metallic 20 underframe including a channel shaped side sill arranged with its web vertically and its flanges extending inwardly, a metallic side plate, metallic sheathing, means securing said sheathing to said side plate, an angular metallic member having a vertical flange secured along the lower margin 25 of said sheathing and a horizontal flange overlapping and secured to the upper inwardly extending flange of said side sill, metallic posts terminating above said side sill, means securing the upper ends of said posts to said side plate, 30 means securing said sheathing to the outside of said posts and brackets securing the lower ends of said posts to said side sill, each of said brackets being disposed between said angular member and the lower end of a post and comprising a horizontal flange secured to the horizontal flange of 35 said angular member and the upper inwardly extending flange of said side sill, a vertical flange secured to the vertical flange of said angular member, a vertical flange extending at right 40 angles from said horizontal and vertical flanges and secured to the lower one of said posts and a depending flange secured to the web of said side sill.

45 6. In a metallic railway house car having a side sill, a side plate, posts secured at their upper ends to said side plate and terminating above said side sill, metallic sheathing secured to said side plate and to the outside of said posts, means securing said sheathing to said sill and means 50 for securing the lower ends of said posts to said sill, said latter means comprising a bracket for each post disposed upon the inside of said means securing said sheathing to said sill and secured to said lower end, each bracket being secured to said sill in two planes at substantially right angles to each other.

7. In a metallic railway house car having a side sill, a side plate, posts secured at their upper ends to said side plate and terminating above said side sill, metallic sheathing secured to said side plate and to the outside of said posts, a member securing said sheathing to said side sill having a vertical flange secured along the lower margin of 60 said sheathing and a horizontal flange secured to said sill, a bracket for securing each post to said sill, said bracket comprising a horizontal flange disposed between the post and the horizontal flange of said member and secured to said side sill, a vertical flange extending from 65 said horizontal flange and secured to the lower end of the post and a depending flange extending downwardly through said horizontal flange of said member and secured to said side sill.

70 8. A metallic railway house car comprising a

metallic underframe including side sills, side plates, posts extending above said sills and secured at their upper ends to said side plates, the outer sides of said posts extending slightly outwardly of said side sill, metallic sheathing secured along the upper margins to said side plates, means securing said sheathing to said outer sides of said posts, said sheathing terminating short of said sills, connecting members having vertical flanges secured along the lower 10 margins of said sheathing and horizontal flanges extending inwardly above said sills and secured thereto and brackets secured to said connecting members, said side sills and the lower ends of said posts, said brackets having depending flanges extending downwardly through openings provided in the horizontal flanges of said connecting members to the outside of said sills, and means securing said depending flanges to said sills.

20 9. In a railway house car having a metallic side sill, a metallic door post of substantially Z-shape in section, said post being arranged with its web substantially parallel to said sill and its flanges at right angles thereto, said web extending downwardly below the top of said sill in outwardly spaced relation thereto and means for securing the lower portion of said post to said sill, said means comprising a bracket having a vertical flange secured to one of the flanges of 25 said post and a flange parallel to the web of said post and secured thereto in spaced relation to said sill, said latter flange extending downwardly below the top of said sill and means for securing said latter bracket flange to said sill.

30 10. In a railway house car having a metallic side sill, a metallic door post of substantially Z-shape in section, said post being arranged with its web substantially parallel to said sill and its flanges at right angles thereto, said web extending 35 downwardly below the top of said sill in outwardly spaced relation thereto, one of said post flanges extending inwardly to overlie and terminate above said sill, and means for securing the lower portion of said post to said sill, said means comprising a bracket having a vertical flange 40 secured to said inwardly extending post flange and a flange parallel to the web of said post and secured thereto in spaced relation to said sill, said latter flange extending downwardly below the top of said sill and means for securing 45 said latter bracket flange to said sill.

50 11. As an article of manufacture, a bracket for the securement of a lower end of a post of a car side wall construction to a side sill of a car underframe comprising a substantially horizontal flange, a substantially vertical flange, spaced flanges extending at right angles from said first-mentioned flanges for securement to a post and a flange depending downwardly from said horizontal flange, said downwardly depending and horizontal flanges being adapted for securement to said side sill and said vertical flange being adapted for securement to said car side wall construction.

55 12. As an article of manufacture, a bracket for the securement of the lower end of a post of a car side wall construction to a side sill of a car underframe comprising a substantially horizontal flange, spaced flanges extending at substantially 60 right angles from said horizontal flange for securement to a post, and a flange depending downwardly from said horizontal flange, said downwardly depending and horizontal flanges being 65 adapted for securement to said sill.

13. A car side wall unit adapted for the conversion of gondola and wooden sheathed house cars to metallic railway house cars, said unit comprising a metallic side sill, a metallic side plate, metallic intermediate and door posts, said intermediate posts extending above said sill, means securing the upper ends of said posts to said side plate and metallic sheathing, means securing the upper margin of said sheathing to 10 said side plate, means securing said sheathing to the outside of said posts, an angular member having a vertical flange secured along the lower margin of said sheathing and an inwardly directed horizontal flange secured to said sill, said 15 horizontal flange being provided with spaced copes and brackets secured to the lower ends of said posts, each of said brackets comprising a vertical flange and a horizontal flange disposed within the angle formed by said flanges of said 20 angular member, the horizontal flange of said bracket lying between said member and the lower end of one of said posts, post attaching flanges extending from said bracket flanges and secured to the lower end of said post and a downwardly 25 depending flange, said latter flange on said brackets for said intermediate posts extending through said copes, means securing said vertical bracket flanges to said vertical flange of said angular member and the lower margin of said 30 sheathing, means securing said horizontal bracket flanges to said side sill, means securing said depending bracket flanges to said side sill.

14. A car side wall unit adapted for the conversion of gondola and wooden sheathed house cars to metallic railway house cars, said unit comprising a metallic side plate, metallic intermediate and door posts, means securing the upper ends of said posts to said side plate, metallic sheathing, means securing the upper margin of 35 said sheathing to said side plate, means securing said sheathing to the outside of said posts, an angular member having a vertical flange secured along the lower margin of said sheathing and an inwardly directed horizontal flange provided with spaced copes and brackets secured to the lower ends of said posts, each of said brackets comprising a vertical flange and a horizontal flange disposed within the angle formed by said 40 flanges of said angular member, the horizontal flange of said bracket lying between said member and the lower end of one of said posts, post attaching flanges extending from said bracket flanges and secured to the lower end of said post and a downwardly 45 depending flange, said latter flange on said bracket for said intermediate posts extending through said copes, and means securing said vertical bracket flanges to said vertical flange of said angular member and the lower margin of said sheathing, and means 50 securing said depending bracket flanges to said side sill.

15. A car side wall unit adapted to be applied to the underframe in the conversion of gondola and wooden sheathed house cars to metallic railway house cars, said unit comprising a metallic side sill, a metallic side plate, metallic intermediate and door posts, said intermediate posts extending above said sill, means securing the upper ends of said posts to said side plate, metallic 55 sheathing, means securing the upper margin of said sheathing to said side plate, means securing said sheathing to the outside of said posts, means securing the lower margin of said sheathing to said side sill, brackets for securing said posts to said side sill, each of said brackets being dis-

posed upon the inside of said last mentioned means and embodying a vertical flange fastened to the lower end of a post, a vertical flange secured to said last mentioned means and a vertical flange extending downwardly through said last mentioned means below the top of said side sill and means securing said downwardly extending flange to said side sill.

16. A railway house car comprising a metallic underframe including a side sill, a metallic side plate, metallic sheathing, means securing said sheathing to said side plate, means securing said sheathing to said side sill, metallic posts terminating above said side sill and secured at their upper ends to said side plate, said sheathing being secured to the outside of said posts, and brackets for securing the lower ends of said posts to said side sill, said brackets being disposed on the inside of said means securing said sheathing to said side sill and each bracket comprising an upwardly extending vertical flange secured to the lower margin of said sheathing, a vertical flange extending at substantially a right angle from said first-mentioned vertical flange and secured to the lower end of a post, and a vertical flange extending downwardly through openings provided in said means securing said sheathing to said side sill and secured to said side sill.

17. In a metallic railway house car, side sills provided with horizontal flanges, side plates, side posts, the spacing between said side sills and the transverse spacing between said posts being such that at least a portion of said posts extends outwardly of said side sills, means securing the upper ends of said posts to said side plates, means securing the lower ends of said posts to said side sills, said latter means having horizontal flanges secured to the horizontal flanges of said sills and vertical flanges secured to the lower ends of said posts, metallic sheathing stopping short of said side sills, means securing said sheathing to said side plates, means securing said sheathing to the outside of said posts and means securing said sheathing to said side sills, said latter means having vertical flanges secured along the lower margin of said sheathing and horizontal flanges disposed below the horizontal flanges of the means securing the posts to the sills and secured to said side sills.

18. A railway house car comprising a metallic underframe including a side sill having a vertical portion and an upper substantially horizontal inwardly extending flange, a metallic side plate, metallic sheathing, means securing said sheathing to said side plate, means securing said sheathing to said side sill, metallic posts terminating above said side sill and secured at their upper ends to said side plate, said sheathing being secured to the outside of said posts, and brackets for securing the lower ends of said posts to said side sill, each of said brackets being formed separately from said means securing said sheathing to said side sill comprising a substantially horizontal flange overlapping and secured to said inwardly extending sill flange, a vertical flange extending upwardly from said horizontal flange and secured to the lower end of one of said posts and a downwardly extending flange secured to said vertical portion of the side sill.

19. A railway house car comprising a metallic underframe including a side sill having a vertical portion and an upper substantially horizontal inwardly extending flange, a metallic side plate, metallic sheathing, means securing said sheathing to said side plate, means securing said sheath-

ing to said side sill, metallic posts terminating above said side sill and secured at their upper ends to said side plate, said sheathing being secured to the outside of said posts, and brackets for securing the lower ends of said posts to said side sill, each of said brackets comprising a substantially horizontal flange overlapping and secured to said inwardly extending sill flange, a vertical flange secured to said sheathing, a vertical flange extending at substantially a right angle to said first-mentioned bracket flanges and secured to the lower end of one of said posts and a downwardly extending flange secured to said vertical portion of said sill.

20. A railway house car comprising a metallic underframe, a metallic side plate, metallic sheathing, means securing said sheathing to said side plate, means securing said sheathing to said underframe, metallic posts terminating above said underframe and secured at their upper ends to said side plate, said sheathing being secured to the outside of said posts and brackets for securing the lower ends of said posts to said underframe, each of said brackets comprising a substantially horizontal flange overlapping and secured to said underframe, a vertical flange extending upwardly from said horizontal flange and secured to the lower end of one of said posts, said bracket flanges being disposed on the inside of the means securing said sheathing to said underframe, each of said brackets comprising also a downwardly extending flange secured to said underframe.

21. A railway house car comprising a metallic underframe, including a side sill having an inwardly extending substantially horizontal flange, a metallic side plate, metallic posts, means securing said posts to said side plate, said posts terminating above said side sill and being disposed so that a portion of each of said posts lies vertically above said sill and a portion extends outwardly of said side sill, metallic sheathing secured to the outside of said posts in outwardly spaced relationship to said sill, means securing said sheathing to said side plate, a metallic member having a vertical flange secured to and along the lower margin of said sheathing and a horizontal flange extending inwardly and overlapping and secured to the horizontal flange of said side sill and brackets for securing the lower ends of said posts to said side sill, each of said brackets comprising a horizontal flange lying between the lower end of one of said posts and the horizontal flange of said metallic member and secured to the inwardly extending flange of said side sill, a vertical flange secured to the vertical flange of said metallic member and a vertical flange extending at right angles to said horizontal and vertical flanges of said bracket and secured to the lower end of said post.

22. A railway house car comprising a metallic underframe, including a side sill having an inwardly extending substantially horizontal flange, a metallic side plate, metallic posts, means securing said posts to said side plate, said posts terminating above said side sill and being disposed so that a portion of each of said posts lies vertically above said sill and a portion extends outwardly of said side sill, metallic sheathing secured to the outside of said posts in outwardly spaced relationship to said sill, means securing said sheathing to side plate, a metallic member having a vertical flange secured to and along the lower margin of said sheathing and a horizontal flange extending inwardly and overlapping and secured to the horizontal flange of said side sill and brackets for securing the lower ends of said posts to said side sill, each of said brackets comprising a horizontal flange lying between the lower end of one of said posts and the horizontal flange of said metallic member and secured to the inwardly extending flange of said side sill, a vertical flange secured to the vertical flange of said metallic member and a vertical flange extending at right angles to said horizontal and vertical flanges of said bracket and secured to the lower end of said post, said first-mentioned vertical flange of each of said brackets being secured to the lower margin of said sheathing.

23. A railway house car comprising a metallic underframe, including a side sill having an inwardly extending substantially horizontal flange, a metallic side plate, metallic posts of Z shape in cross section, said posts being arranged with their webs at right angles to the longitudinal center line of the car and their inner and outer flanges parallel to said center line, means securing said posts to said side plate, said posts terminating above said side sill and having their outer flanges disposed outwardly of said side sill, metallic sheathing secured to the outside of said outer post flanges in outwardly spaced relationship to said side sill, means securing said sheathing to said side plate, a metallic member having a vertical flange secured to and along the lower margin of said sheathing and a horizontal flange extending inwardly below the lower ends of said posts, said horizontal flange overlapping and secured to the horizontal flange of said side sill, and a bracket for securing each post to said side sill, each of said brackets comprising a horizontal flange lying between the lower end of one of said posts and the horizontal flange of said metallic member and secured to the horizontal flange of said side sill, a vertical flange secured to the vertical flange of said metallic member and a vertical flange extending at right angles to said horizontal and vertical flanges of said bracket and secured to the web of said post.

FRANK DITCHFIELD. 60

CERTIFICATE OF CORRECTION.

Patent No. 2,125,047.

July 26, 1938.

FRANK DITCHFIELD.

It is hereby certified that error appears in the printed specification of the above numbered patent requiring correction as follows: Page 4, first column, line 42, claim 5, after "lower" insert the words end of; and that the said Letters Patent should be read with this correction therein that the same may conform to the record of the case in the Patent Office.

Signed and sealed this 30th day of August, A. D. 1938.

Henry Van Arsdale

(Seal)

Acting Commissioner of Patents.
